SELF-COMPLEMENTING GAS COUNTER TUBE

Robert B. Koehler, Hopewell Junction, and Richard K. Richards, Poughkeepsie, N. Y., assignors to International Business Machines Corporation, New York, N. Y., a corporation of New York

Application December 8, 1953, Serial No. 396,804

6 Claims. (Cl. 313—196)

This invention relates to multi-cathode glow discharge devices and more particularly to a gaseous counter tube for effecting storage of positive and negative digital values. The improved counter tube is of the type disclosed in the copending United States patent application, Serial No. 301,675, which was filed July 30, 1952, on behalf of Richard K. Richards.

Devices of the type disclosed in the above identified application comprise, in general, an array of electrodes adapted for use as glow cathodes and a single anode arranged in cooperative relation with and common to each of the cathode electrodes. In a decimal type accumulator, ten digit representing cathodes and ten transfer cathodes are alternately interspersed with one another to form a closed glow transfer path having ten stable glow discharge positions. Ten complement cathodes are provided, with pairs interspersed between certain of said digit cathodes representative of complement values, in providing the self-complementing features which are described in the aforementioned application.

An object of the present invention is to provide an improved cathode structure for gaseous counter tubes whereby transfer of the glow discharge from one electrode to another may be effected at increased speed and with increased reliability.

In accordance with another feature of the invention an improved electrode and supporting structure is provided whereby the tube elements lend themselves readily to quantity production and retain stable characteristics for increased operating periods.

Still another object of the invention is to provide an improved electrode insulating means for confining the glow discharge to a particular area of cathode surface, which insulation means is capable of withstanding high temperatures, has a low vapor pressure and is sufficiently durable to undergo mass production processes.

Another object of the invention is to provide a cathode structure having an improved glow transfer mechanism.

A still further object is to provide a glow transfer storage tube having a more simplified and sturdy construction and requiring little or no special tooling to make the component parts.

Other objects and features of the invention will be pointed out in the following description and claims and illustrated in the accompanying drawings, which disclose, by way of example, the principle of the invention and the best mode, which has been contemplated of applying that principle.

In the drawings, which consist of two sheets, having five figures:

Fig. 1 is a diagrammatic view of the electrode arrangement of a self-complementing glow counter tube showing the circuit connections.

Fig. 2 is an enlarged view of the tube with a portion of the envelope broken away and showing the improved structure.

Fig. 3 is a view of the tube at right angles to the sec-

2

tion in Figure 2 and showing additional features of electrode structure and mounting details.

Fig. 4 illustrates a single cathode element with transfer wire and circuit connector lead attached prior to bending and securing to a supporting member.

Fig. 5 is a greatly enlarged view of several electrodes showing the mounting tabs and transfer wires.

Referring now to the drawings, the glow discharge device illustrated in Figure 1 comprises ten digit representing cathodes D-0 to D-9 inclusive, representing the digits 0-9 respectively, ten transfer cathodes T-0 to T-9 inclusive, ten complement cathodes C-0 to C-9 inclusive, and a common anode A equidistant from the ends of each of the several cathodes and represented by a rectangle.

Transfer wire *t* are provided to effect transfer of the glow discharge therealong from the cathode adjacent the free end to the cathode to which the other end is attached, when an appropriate voltage difference exists between the two cathodes.

The anode A is connected through a resistor, not shown, to a suitable source of positive voltage indicated as terminal B+. The complement cathodes C-0 to C-9 inclusive, are connected together and to a terminal C. The digit representing cathodes D-1 to D-8 inclusive are connected together and to a suitable source of voltage, less positive than B+, at a terminal D. The digit representing cathodes D-0 to D-9 are connected to output terminals F and G respectively, which are connected to the same source of voltage to which the D-1 to D-8 cathodes are connected through other resistances, not shown. The transfer cathodes T-0 to T-9 inclusive, are connected together and to a terminal T.

The manner of operation of the tube is described in detail in the aforementioned application and will be but briefly discussed here. Initially, the terminal F is pulsed negatively and a single stable glow discharge is established between the cathode D-0 and the anode A. A negative pulse to be stored in the tube is thereafter

40 applied to the terminal T and the voltage difference between the transfer cathode T-1 and the anode A becomes greater than that between cathode D-0 and the anode so that the glow transfers along the associated transfer wire *t* to the cathode T-1. As the negative pulse terminates, the voltage between cathode T-1 and the anode becomes less than that between cathode D-1 and the anode and the glow accordingly again transfers along the transfer wire *t* attached to cathode D-1 and exists stably at this latter cathode position until a succeeding

45 pulse is applied to the terminal T. A similar transfer occurs with each input pulse applied and the glow is stepped along from one D cathode to another in succession. On arrival at cathode D-9 this cathode goes more positive and then becomes less positive as the tenth pulse is applied, completing one cycle of operation and producing an indication of this condition on terminal G.

50 While an output signal is taken from the the D-9 cathode, as illustrated, it is obvious that any other one or ones of the cathodes may be used for output purposes by connecting them separately.

55 If the digit stored is in true form it may be converted to its nine's complement by pulsing the terminal C negatively. This causes the existing glow to prefer the C cathode and migrate along the associated transfer wire *t* attached thereto. Thereafter, as the complement pulse

60 terminates, the glow moves along the transfer wire *t* attached to the D cathode representing the nine's complement value of the stored digit and remains stably at this D cathode position. A second complementing pulse will cause the glow to shift to the other of the pair of associated C cathodes and thence to the original D cathode position in a like manner.

Fig. 3 is a view of the tube at right angles to the sec-

Referring now to Figure 2, the cathodes shown schematically in Fig. 1 as tubular elements are seen to be generally U-shaped and are supported on strips 11 of mica or other suitable insulating material, which are in turn mounted within an envelope E. The cathodes are shown in the same relative positions as in Figure 1 and are mounted alternately on opposite sides of the strips 11 so that the mica supports function additionally as shield members and prevent random glow transfer between adjacent electrodes. The cathodes are arranged on four strips 11 and are affixed thereto by means of tabs 12 which pass through perforations in the mica and are clinched as shown in greater detail in Figure 5. The mica strips are positioned with respect to each other by spacing bars at each end of the structure and which are labeled elements s.

A lateral view of the arrangement is shown in Figure 3 and in this illustration it may be seen that the upper ends of the U-shaped elements are formed at an angle. The purpose of this structural feature is to provide a direction of preferred glow transfer or so called preference mechanism as it has been determined that a glow existing between the anode and inner surface of the U-shaped member tends to emerge from the latter in a direction perpendicular to the plane of the opening. The free end of a transfer wire may then be placed in a more reliable region of the glow discharge and the overall operation and stability of the tube enhanced.

The glow discharge is confined to the interior surface of the cathode to prevent random transfer and the cathode is made relatively long to permit operation at high current magnitudes, about four milliamperes for the $\frac{3}{8}$ inch length employed. Elimination of glow discharge from the exterior electrode surface has heretofore been accomplished by coating the exterior with carbon, as described in detail in the application of Richard K. Richards, Serial No. 192,199, which was filed October 26, 1950. The carbon coating, however, being a conductive material was found to sustain a glow discharge at indeterminate periods and aluminum cathodes having anodized exterior surfaces have been found to produce improved results. The anodizing process provides a dense translucent coating of insulating oxide about 0.001 inch thick which has a low vapor pressure and is capable of withstanding high temperatures without deterioration as in an outgassing process or under prolonged tube operation.

Forming the cathode electrodes as U-shaped members mounted by tabs, in the manner described, facilitates quantity production of the glow counter tube as the mica support strips 11 and the cathodes may be readily formed by stamping or other like processes. A cathode 13 similar to the D and T cathodes and formed as a flat element from a sheet of aluminum anodized on one surface, is shown in Figure 4. The layer of anodized material is indicated by a label 15. The manufacturing steps thereafter include chemical cleaning followed by washing and drying to remove the oxides produced by normal exposure to air and other undesirable materials adhering to the active cathode surfaces in handling. Cleaning may be accomplished by immersion in a solution of HNO_3 and HF or in a commercial degreasing and de-oxidizing bath. The chemical cleaning process provides a suitable surface to which the transfer wire t and a circuit connector lead 14 are welded. These leads are formed of platinum and nickel respectively, however other materials may be employed with satisfactory results. Removal of the oxide film lowers the surface resistance and work function of the cathode surface and thereby provides more uniform electrical characteristics.

After the platinum and nickel wires are affixed, as by welding, the cathode elements are bent into a U-shape, mounted on the mica strips 11 and the multiple strip assembly mounted in the tube envelope for outgassing and introduction of a suitable ionizable atmosphere.

While there have been shown and described and pointed out the fundamental novel features of the invention as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

10. What is claimed is:
1. A gaseous discharge storage tube of the glow transfer type wherein a glow discharge is sequentially transferred from one preselected position to another to store digit representing electrical impulses including, an anode, a plurality of aluminum cathodes formed as elongated U-shaped electrodes, a coating of anodized aluminum oxide on the exterior surfaces of said cathodes to confine a glow discharge between said anode and said cathodes to the interior surfaces of the latter, a plurality of insulating strips, means supporting said cathodes on said strips including tabs on said U-shaped electrodes whereby the upper ends of each of said cathodes are equidistantly spaced from said anode.
  2. A gaseous discharge storage tube comprising an envelope, at least one insulating support strip mounted within said envelope, a plurality of elongated U-shaped cathode electrodes supported on said strip by means of tabs, a glow transfer wire for each said cathode having one end affixed to said cathode and a free end extending in proximity to a region of stable glow discharge of an adjacent cathode, and an anode arranged in said envelope equidistant from one end of each of said cathodes.
  3. A gaseous discharge tube as set forth in claim 2 wherein said U-shaped cathodes are affixed to said strip in such a manner that a cylindrical volume is enclosed and the upper end of said U-shaped electrode is formed at an angle other than 90° to the longitudinal axis of the electrode.
  4. A gaseous discharge storage tube comprising an envelope, a plurality of elongated cylindrical cathode elements mounted within said envelope each having one end thereof formed at an angle other than 90° to its longitudinal axis, an anode mounted within said envelope and arranged equidistant from the angled ends of each of said cathodes, and a glow transfer wire for each of said cathodes having one end affixed to the associated cathode at a point thereon nearest said anode and a free end extending in proximity to the angled end of an adjacent cathode.
  5. A gaseous discharge storage tube of the glow transfer type wherein a glow discharge is sequentially transferred from one preselected position to another, a plurality of cathodes arranged in a closed glow transfer path, said cathodes being formed as elongated U-shaped members each having one end thereof formed at an angle other than 90° to its longitudinal axis, an anode arranged equidistant from the angled ends of each of said cathodes, and a glow transfer wire for each of said cathodes having one end affixed to the associated cathode at a point thereon nearest said anode and a free end extending in proximity to the angled end of an adjacent cathode.
  6. A gaseous discharge storage tube comprising an envelope, at least one insulating mica support strip mounted within said envelope, a plurality of elongated U-shaped aluminum cathode electrodes supported on said strip by means of tabs and with alternate ones of said electrodes positioned on opposite sides of said strip, a coating on the exterior surface of said cathodes comprising anodized aluminum oxide whereby a glow discharge is confined to the interior surface thereof, each of said cathode electrodes having one end formed at an angle other than 90° to its longitudinal axis, an anode mounted within said envelope and positioned equidistant from

the angled ends of each of said cathodes, a glow transfer wire for each of said cathodes having one end affixed to the associated cathode at a point thereon nearest said anode and a free end extending over said mica strip in proximity to the angled end of an adjacent cathode electrode.
